WILLIAM H. POLLARD, OF SENECA FALLS, NEW YORK, ASSIGNOR TO
DOWNS & CO.'S MANUFACTURING COMPANY, OF SAME PLACE.

Letters Patent No. 73,038, dated January 7, 1868.

IMPROVEMENT IN PUMP-VALVES.

The Schedule referred to in these Letters Patent and making part of the same.

TO ALL WHOM IT MAY CONCERN:

Be it known that I, WILLIAM H. POLLARD, of Seneca Falls, in the county of Seneca, and State of New York, have invented a certain new and useful Improvement in Pumps; and I do hereby declare that the following is a full and exact description thereof, reference being had to the accompanying drawings, making part of this specification.

Figure 1 is a central vertical section of the lower portion of my improved pump.

Figure 2, a perspective view of the under side of the induction-valve.

Like letters of reference indicate corresponding parts in both figures.

My improved pump is intended more particularly for use in wells formed by driven tubing, where much sand is raised.

The invention consists in the employment, in combination with an elevated valve-seat, of a rubber or equivalent disk, of concave form, attached on the under side of the valve, and acting in such manner, by its expansion, in closing, as to sweep off all sand from the valve-seat, and thus insure a close and tight packing.

As represented in the drawings, A is a pump-cylinder of ordinary form, B the plunger, C the base of the pump, and D is the end of the tubing, screwing therein. The base of the pump is provided with an elevated seat, *a*, leaving a deep groove, *b*, all around, for the deposit of the sand that is drawn into the pump. The induction-valve consists of a ring, E, of leather, fitting between the shoulders *c c*, and provided with a tongue, *d*, with which is connected a weight, *f*. On the bottom of this valve is attached a disk, *g*, of concave form on its under side, preferably made of rubber or leather, and of such size as to cover the valve-seat when it strikes thereon.

The great difficulty in operating pumps connected with driven tubing, occurs from the sand which is drawn in and obstructs the lower valve. To remedy this, the valve-seat has before been elevated, to allow the sand to deposit outside; but in this case, even, the grains lodge upon the top of the seat, and prevent the valve from closing tightly. I prevent this difficulty by the employment of the concave disk *g*, which, when it strikes the seat in the closing of the valve, spreads out or expands, and thus brushes the sand from place on the seat. This device is very effective for this purpose, and produces a very tight packing in the closing of the valve. Since the expansive action of the disk upon the seat is required to be but very slight, it will be seen that under ordinary circumstances there can be no danger from rupture or permanent expansion, if the disk is well made, and of sufficient thickness. If there should be difficulty from this source, however, the disk may be stiffened by radial strips of light spring metal riveted thereto.

In addition to the special advantage above mentioned, the concavity of the disk allows it at all times to fit and adapt itself to the top of the seat, whether the valve proper stands in a line with the seat or not. A simple plane surface would not do this.

I do not claim broadly an elevated valve-seat, as I am aware that it has been before known; but,

What I claim as my invention, and desire to secure by Letters Patent, is—

The combination of the concave disk *g* of the valve with the elevated seat *a*, arranged as described, and operating in the manner and for the purpose specified.

In witness whereof, I have hereunto signed my name, in the presence of two subscribing witnesses.

WILLIAM H. POLLARD.
